C. A. MURDOCK.
TRACK LAYING TRACTOR.
APPLICATION FILED APR. 9, 1919.

1,320,165.

Patented Oct. 28, 1919.

UNITED STATES PATENT OFFICE.

CHARLES A. MURDOCK, OF STOCKTON, CALIFORNIA, ASSIGNOR OF ONE-HALF TO
FREDERICK L. LEVY, OF STOCKTON, CALIFORNIA.

TRACK-LAYING TRACTOR.

1,320,165.

Specification of Letters Patent. Patented Oct. 28, 1919.

Application filed April 9, 1919. Serial No. 288,691.

To all whom it may concern:

Be it known that I, CHARLES A. MURDOCK, a citizen of the United States of America, residing at Stockton, in the county of San Joaquin and State of California, have invented certain new and useful Improvements in Track-Laying Tractors; and I do declare the following to be a clear, full, and exact description of the same, reference being had to the accompanying drawings, and to the characters of reference marked thereon, which form a part of this application.

This invention relates to improvements in track laying or endless track tractors, the principal object of the invention being to so construct the tractor, and particularly the track feature thereof, that there will be a minimum of track sections and joints and hence fewer parts to wear out.

Another feature of my invention is the elimination of the usual sprocket drive for the track, which ordinarily is in the form of a chain of some kind, necessitating a high grade of metal in the construction thereof.

My improved track sections are in the form of slabs or great area and length rather than chains, and I am enabled to form an endless drive therewith by the use of polygonal wheels or tumblers in the manner more fully set forth hereinafter.

I have here described and shown particularly on Figure 1 of the drawings, a form of tractor having the endless track feature only on one side thereof, the other side having merely a balance or supporting wheel. This type is particularly adapted to be used in the pulling of plows, where sharp turns are desirable, and which can be made in this case by turning the tractor about the supporting wheel as a pivot. However, it is to be understood that I do not limit myself to having only one track, but may use two if so desired.

Another object of the invention is to produce a simple and inexpensive device and yet one which will be exceedingly effective for the purposes for which it is designed.

These objects, I accomplish by means of such structure and relative arrangement of the parts as will fully appear by a perusal of the following specification and claims.

On the drawings, similar characters of

reference indicate corresponding parts in the several views.

Fig. 1 is a side elevation of my improved tractor.

Fig. 2 is a cross section through the track unit taken on a line 2—2 of Fig. 1.

Fig. 3 is a fragmentary plan of a track section joint.

Fig. 4 is a longitudinal section of the same taken on a line 4—4 of Fig. 3.

Fig. 5 is a cross section of a modified manner of assembling a polygonal track-wheel or tumbler.

Referring now more particularly to the characters of reference on the drawings, the numeral 1 designates the outer longitudinal frames of the tractor which are suitably spaced apart and have shafts 2 mounted under the same and transversely thereof at each end, and a predetermined distance apart.

Keyed to the shafts 2 are equal sized wheels or tumblers 3 and 4 preferably of rectangular periphery, the rear one 4 of such wheels being connected to a chain sprocket drive 5 operated in the usual manner by a power plant 6 mounted on the frame of the tractor to one side of the outer frame.

Each of the tumblers 3 and 4 comprises a pair of such rectangular members 3^a and 4^a, respectively, having hubs 7 projecting therebetween and adapted to abut when in position on the shafts 2 so that there is a considerable space, as at 8, between such rectangular portions.

Each corner of the members 3 and 4 has a wearing strip 9 of hard steel or similar long wearing material. Adapted to pass around the tumblers 3 and 4 are track sections 10 linked together, each section having a length from center to center of links equal to the length of one of the sides of the members 3 and 4.

Each track section comprises a tread portion or shoe 11 extending across the members 3^a and 4^a or as wide as may be desired and still pass between the frames 1. These shoes may be constructed of wood of any thickness, and if so constructed may be sheathed in metal as at 12.

Central of each shoe and lengthwise there-

of on the inner face of the same is a channel iron 13, or similar structure, the width of such member being sufficient to permit it to pass in the space 8 between the members 3^a and 4^a.

These channels are of a height sufficient to conceal a hinge strap 14 secured to one end of each shoe inside the channel thereon, the pin 15 of the hinge being rigidly secured 10 to the sides of the channel of the adjacent shoe and turning in the strap 14, there being a grease cup 16 secured to each strap and likewise concealed between the sides of the channel 13.

15 Pivottally mounted under the frames 1 on a shaft 17 on brackets 18 depending from the frames 1, is a truck-frame 19 carrying a pair of rollers 20 on each end thereof, the rollers riding on the inner faces of the shoes 20 11 at a level considerably below the level of the bottom of the members 3 and 4 and straddling the channels 13 thereof and forming guides for the track sections between the tumblers 3 and 4.

25 The pivotal shaft 17 is preferably central between the shafts 2 and also on a line with the shaft of a supporting wheel 21 mounted to the frame of the tractor on the farther side thereof from the endless track unit.

30 A tiller wheel 22 is mounted to the frame at the forward end thereof, the tiller wheel being operable from the driver's seat 23 by means of the steering wheel 24 and suitable mechanism connected therewith.

35 Thus it will be seen that by the use of this tiller wheel, and by any suitable means to brake and hold the supporting wheel 21, the tractor may be turned on that side about the wheel 21 as a pivot, thus making a very 40 sharp turn.

Also it will be noted that the main weight of the tractor is carried by the rollers 20 and the shoes therebeneath, relieving the tumblers 3 and 4 of this weight, and thus making it easier for them to turn without great 45 strain on their shafts and bearings and doing away with the necessity of making these parts very heavy and cumbersome.

Also by reason of the fact that the truck 50 19-20 holds the members 3 and 4 well above it, and has a rocking motion on the shaft 18 which is on a line, or may be one with, the shaft of the wheel 21, the tractor is enabled to tilt about this point, when going 55 over unevennesses in the ground surface, without the corners of the members 3 and 4 coming close enough to the ground to lift the tractor with the turning thereof.

If it is desired to utilize a track having a 60 pair of spaced hinges instead of the one here described, the members 3^a and 4^a may be reversed in position on the shafts, and bolted together to form a single wide face, as shown in Fig. 5. In this type the hinges of 65 the tracks would be on the outside of the

tumblers, instead of between, and would of course necessitate certain changes in the detail of construction of the track sections, but would not change the principle of operation thereof.

70 From the foregoing description it will be readily seen that I have produced such a device as substantially fulfills the object of the invention as set forth herein.

75 While this specification sets forth in detail the present and preferred construction of the device, still in practice such deviations from such detail may be resorted to as do not form a departure from the spirit of the invention, as defined by the appended 80 claims.

Having thus described my invention, what I claim as new and useful and desire to secure by Letters Patent is:—

1. A tractor including a frame, polygonal 85 sided tumblers turnably mounted at each end of the frame, one of the tumblers being operatively connected with the power plant of the tractor, an endless track passing around the tumblers, each link of the track 90 having a length equal to that of each side of the tumblers, and means depending from the frame and pivoted thereto whereby the weight of the tractor is taken off the tumblers and the tractor may oscillate about 95 such pivotal point.

2. A tractor including spaced longitudinal frames, rectangular tumblers turnably mounted between the frames, one of the tumblers being operatively connected with the 100 power plant of the tractor, linked track sections passing over the tumblers and adapted to contact with the ground at a lower level than the lowest point of the tumblers, each track section having a length equal to that 105 of one side of the tumblers, means whereby such position of the track sections is maintained, and means on the track sections whereby the same are guided on the tumblers.

3. A tractor including spaced longitudinal frames, tumblers turnably mounted between the frames, each of the tumblers comprising a pair of vertical rectangular members spaced apart and one of the same being 115 operatively connected with the power plant of the tractor, linked track sections passing over the tumblers and adapted to contact with the ground at a level lower than the lowest point of the tumblers, each track section having a length equal to that of one side of the tumblers, guide members projecting from the inner faces of the track sections and adapted to pass between the rectangular members of the tumblers to 120 guide the track sections thereon, and hinges on each track section between the guide members thereof.

4. A tractor including a frame, polygonal sided tumblers turnably mounted at each 125

end of the frame, one of the tumblers being operatively connected with the power plant of the tractor, an endless track passing around the tumblers, each link of the track having a length equal to that of each side of the tumblers, and means whereby the track sections adjacent the ground are adapted to contact therewith at a level lower than that of the lowest point of the tumblers, such means including a frame pivotally mounted under the tractor frame for oscillatory movement relative thereto, and rollers turnably mounted at each end of the last named frame and adapted to rest on the inner faces of the track sections when the latter are adjacent the ground. 5

5. A tractor including a frame, polygonal sided tumblers turnably mounted at each end of the frame, one of the tumblers being operatively connected with the power plant of the tractor, an endless track passing around the tumblers, each link of the track having a length equal to that of each side of the tumblers, and means whereby the track sec- 10

tions adjacent the ground are adapted to contact therewith at a level lower than that of the lowest point of the tumblers, such means including a frame pivotally mounted under the tractor frame for oscillatory movement relative thereto, and rollers turnably mounted at each end of the last named frame and adapted to rest on the inner faces of the track sections when the latter are adjacent the ground, the center of oscillation of the roller-frame being on a transverse line with that of a supporting wheel on the side of the tractor opposite from the endless track whereby when the plane of contact of the tiller wheel is altered, the tractor will tilt about the oscillatory point as a pivot. 35

In testimony whereof I affix my signature in presence of two witnesses.

CHARLES A. MURDOCK.
